UNITED STATES PATENT OFFICE.

DONALD H. PELAAR, OF KALAMAZOO, MICHIGAN.

EQUALIZER.

Application filed April 19, 1924. Serial No. 707,781.

To all whom it may concern:

Be it known that I, DONALD H. PELAAR, a citizen of the United States, residing at Kalamazoo, in the county of Kalamazoo and 5 State of Michigan, have invented certain new and useful Improvements in Equalizers, of which the following is a specification.

The present invention relates to an equalizer particularly adapted for the operation 10 of four wheeled brakes which are now coming into common use upon automobiles.

The prime object of the invention is to provide a device of this nature possessing a simple and efficient construction which 15 may be readily installed upon automobiles of various types and which will be reliable in operation, comparatively inexpensive to manufacture, durable, strong, and otherwise well adapted to the purpose for which 20 it is designed.

With the above and numerous other objects in view as will appear as the description progresses, the invention resides in certain novel features of construction, and in 25 the combination and arrangement of parts as will be hereinafter more fully described and claimed.

In the drawing:

Figure 1 is a horizontal section through an 30 equalizer embodying my invention,

Figures 2, 3 and 4 are sections taken substantially on the lines 2—2, 3—3 and 4—4 respectively of Figure 1, and

Figure 5 is a horizontal section through 35 the modified form of the invention.

Referring to the drawing in detail it will be seen that 1 designates a casing which is preferably square in formation and having associated therewith a cover plate 2.

40 A pin 4 extends centrally through the casing and also through the cover or lid plate 2 being held in place by a nut 5 or in any other suitable manner. A rotary member 6 is mounted on the pin within the casing

45 and in the present instance includes a hub 7 and a pair of spaced plates 8 of circular construction. Suitable roller bearings 9 are preferably provided within the hub 7 in order that the rotary member may operate

50 freely on the pin. A washer 10 spaces the rotary member from the bottom of the casing.

A plurality of pulleys 11 are rotatably mounted between the plates 8 on pins 12 and 55 13. The pins 13 are arranged in a circle equidistant from each other and the pins 12

are likewise arranged except that the circle of pins 12 would be smaller than that of pins 13 and thus rollers 11 on pins 13 extend slightly beyond the periphery of the plates 60 8. An endless belt 14 is trained about the pulleys 11 on pins 12 and the runs of the belt extend between the rollers 11 on pins 12 and the rollers 11 on pins 13 as is illustrated to advantage in Figure 1 thus forming, in the present instance, four loops 15 which are engaged about pulleys 16 journaled in yokes 17 carried by a cable 18. These cables 18 pass about guide rollers 19 mounted in the casing 1 and are engaged with rods 20 passing through the sides of the casing into cylindrical housings 21 in which are disposed springs 22 engaging stops 23 on the rods 20 and the sides of the casing. 65 70 75

In the preferred embodiment of the invention as shown in Figures 1 to 4 inclusive the crank 25 is fixed by means of screws 26 to one of the plates 8 for the rotation of the rotary member by means of a rod 27 which, of course, would lead to the brake 80 pedal conveniently located in the automobile. It will thus be seen that when the rod 27 is pulled the rotary member is turned by the crank 25 thus causing the endless belt 14 to pull upon the cables 18 so as to move 85 the rods 20 into the casing 1. It is, of course, understood that the rods 20 are connected to the usual operating means adjacent the brake for expanding or contracting them depending upon the kind of brake used. It will 90 thus also be seen that an equal pressure may be imparted to all four brakes.

In the modification shown in Figure 5 instead of crank 25 I use a pinion 30 keyed to the pin 4 as is also the rotary member. 95 A rack bar 31 meshes with the pinion 30 and is pulled in one direction by rod 27 and in the other direction by a spring 32. A roller 33 and rollers 34 are mounted on the cover plate 2 so as to hold this rack bar 31 100 in mesh with the pinion 30. Thus when the pinion is moved the gear is rotated and the rotatable member turned and otherwise the device operates similar to the other modification. 105

It is thought that the construction and operation of this invention should now be clearly understood without any more detail description thereof. While the preferred embodiment of this invention has been described in detail, it will be understood that I do not wish to be limited to the particular 110

construction set forth, since the various changes in the form, material, proportions, and arrangement of parts and in the details of construction, may be resorted to without departing from the spirit and scope of the invention as hereinafter claimed or sacrificing any of its advantages.

Having thus described my invention, what I claim as new is:

- 10 1. An equalizer of the class described including a rotatable member, a plurality of pulleys mounted in the rotatable member, and an endless cable trained over and above the pulleys so as to form loops, pulleys engaged in the loops, and means attached to the pulleys for operation of mechanisms.
- 15 2. An equalizer of the class described including a casing, a rotary member in the casing, a plurality of pulleys mounted on the rotary member, an endless member inter-trained about and among the pulleys so as to form a plurality of loops, pulleys in the loops, means attached to the pulleys for the operation of mechanism, and means for rotating the rotary member.
- 20 3. An equalizer of the class described including a casing, a rotary member mounted in the casing, a plurality of pulleys mounted on the rotary member, an endless belt trained over and among the pulleys so as to form a plurality of loops, pulleys disposed in the loops, cables connected to the last mentioned pulley, rods connected to the cables, and passing through the casing, cylindrical housings mounted on the casing to receive the rods, springs in the housings, and stops on the rods so that said springs engage the stops and against the sides of the casing so as to normally hold the cables taut.
- 25 4. An equalizer of the class described including a casing, a rotary member mounted in the casing, a plurality of pulleys mounted on the rotary member, an endless belt trained over and among the pulleys so as to form a plurality of loops, pulleys disposed in the loops, cables connected to the last mentioned pulley, rods connected to the cables, and passing through the casing, cylindrical housings mounted on the casing to receive the rods, springs in the housings,

and stops on the rods so that said springs engage the stops and the sides of the casing, and means for rotating the rotary member.

5. An equalizer of the class described including a casing, a rotary member mounted in the casing and including a pair of spaced plates, a plurality of pulleys arranged in a circle between the plates, a second series of pulleys arranged in a circle between the plates one of the latter being disposed between each pair of the former, the latter circle being larger than the former circle, an endless belt trained over the first series of pulleys so as to form loops the runs of which are disposed one on each side of each pulley of the second series, and means engaging the loops for actuating mechanisms, and means for rotating the rotary member.

6. An equalizer of the class described including a casing, a plurality of cylindrical housings mounted on the casing, springs in the housings, rods in the housings, stops on the rods engaging the springs, said rods piercing into the casing, cables engaged on the inner ends of said rods, yokes on said cables, pulleys journaled in said yokes, an endless belt trained over said pulleys, a rotary member mounted centrally within the casing, a plurality of pulleys in the rotary member, said belt being also trained over the latter mentioned pulleys, and means for turning the rotary member thereby pulling inwardly upon the first mentioned pulleys, also the cables and the rods attached thereto for actuation of mechanisms.

7. An equalizer of the class described including a rotatable member, an endless cable, a plurality of elements mounted on the rotatable member, said endless cable being trained over the plurality of elements to form loops, and means engaged in the loops and adapted to be attached to mechanisms for actuation thereof upon rotation of the rotatable member.

In testimony whereof I affix my signature in presence of two witnesses.

DONALD H. PELLAAR.
